CLAIM

The ornamental design for a knife sharpener, as shown and described.

DESCRIPTION

FIG. 1 is a perspective view of the knife sharpener;
 FIG. 2 is a front elevation view thereof;
 FIG. 3 is a rear elevation view thereof;
 FIG. 4 is a right elevation view thereof;
 FIG. 5 is a left elevation view thereof;
 FIG. 6 is a top plan view thereof;
 FIG. 7 is a bottom plan view thereof;
 FIG. 8 is a perspective view showing the knife sharpener in a second position of use, wherein a sharpening rod is in an extended position of use;
 FIG. 9 is a perspective view of the knife sharpener in a third position of use, wherein a foot is deployed;
 FIG. 10 is a front elevation view thereof;
 FIG. 11 is a rear elevation view thereof;
 FIG. 12 is a right elevation view thereof;
 FIG. 13 is a left elevation view thereof;
 FIG. 14 is a top plan view thereof; and,
 FIG. 15 is a bottom plan view thereof.

The broken lines depict portions of the knife sharpener in which the design is embodied that are not considered part of the claimed design.
